UNITED STATES PATENT OFFICE.

EDWARD LAWSON FENERTY, OF HALIFAX, NOVA SCOTIA, CANADA.

SHOVEL.

SPECIFICATION forming part of Letters Patent No. 299,530, dated June 3, 1884.

Application filed November 23, 1883. (No model.)

To all whom it may concern:

Be it known that I, EDWARD L. FENERTY, of Halifax, in the county of Halifax, Province of Nova Scotia, Dominion of Canada, have invented a certain new and useful Improvement 5 in Shovels, of which the following is a description sufficiently full, clear, and exact to enable any person skilled in the art or science to which said invention appertains to make and 10 use the same, reference being had to the accompanying drawings, forming a part of this specification, in which—

Figure 1 is an isometrical perspective view showing the bottom or under side of my improved shovel; Fig. 2, a like view showing its 15 top or upper side; Fig. 3, a view of the socket detached; Fig. 4, a vertical transverse section taken on the dotted line $x x$ in Fig. 2; Fig. 5, a vertical transverse section showing 20 a modification of my improvement.

Like letters and figures of reference indicate corresponding parts in the different figures of the drawings.

This invention relates to shovels or spades 25 and sockets; and it consists in a shovel and a socket of peculiar construction, as hereinafter described and claimed.

In Fig. 1, E is the blade, and G the socket, a depression, a , which is Δ -shaped in cross- 30 section and V -shaped in area, being formed in the lower side of the blade at its upper edge, as best seen in Figs. 2, 4, and 5.

The socket for receiving and holding the handle and the flange by which it is attached 35 to the blade of the shovel are integral, or formed of a single piece of metal, as best seen in Fig. 3, the flange h being V -shaped and struck up and bent or formed to fit the depression a , but of such width or size as not to extend below the

lower surface of the blade. The socket proper, 40 or that portion of the socket which is designed to receive the handle of the shovel, is formed by curving or bending the sides rr inwardly at their centers and upper ends, and slightly curving them downwardly and outwardly, as 45 seen at $t t$, at their lower ends, thereby bracing and greatly strengthening the socket at the point where it is subjected to the severest strain in using the shovel. The socket is also bent or curved to form a goose-neck, as best 50 shown at w in Figs. 1 and 2; but this bend may be slight or entirely omitted, if desired. Both the socket and its flange may be made of cast metal, either malleable or otherwise, if desired, although wrought-iron or steel is preferable. 55

Having thus explained my invention, what I claim is—

A shovel having a blade provided on its under side with a depression which gradually 60 decreases in depth and diminishes in size from its outer to its inner end for receiving the attaching tang or flange of the handle-socket, said depression being V -shaped in area and Δ -shaped in cross-section, and a handle-socket 65 provided with an attaching tang or flange which is V -shaped in area and Δ -shaped in cross-section, and adapted to fit said depression, said tang or flange being integral with the body of the socket and riveted to the blade 70 of the shovel by rivets, the lower ends of which are within said depression and above the plane of the under side of the blade at said depression, substantially as set forth.

EDWARD LAWSON FENERTY.
